UNITED STATES PATENT OFFICE.

RAYMOND A. PERRY, OF SAN FRANCISCO, CALIFORNIA, ASSIGNOR OF ONE-HALF TO ATLANTIC GULF AND PACIFIC COMPANY, OF NEW YORK, N. Y., AND SAN FRANCISCO, CALIFORNIA, A CORPORATION OF WEST VIRGINIA.

DREDGER.

SPECIFICATION forming part of Letters Patent No. 703,817, dated July 1, 1902.

Application filed November 6, 1900. Serial No. 35,630. (No model.)

To all whom it may concern:

Be it known that I, RAYMOND A. PERRY, a citizen of the United States, residing in the city and county of San Francisco, State of California, have invented an Improvement in Dredgers; and I hereby declare the following to be a full, clear, and exact description of the same.

My invention relates to improvements in apparatus for dredging and excavating soil, and is especially designed to be used where such excavations are made in material which is submerged beneath water.

It consists in a mechanism by which the excavation is produced by a forward-reciprocating movement in the line of the boat and apparatus, means for the allowing of such movement and the corresponding extension of the conveying-pipes, and mechanism for reTRACTING the apparatus after the forward cut has been completed and placing it to make another cut parallel with the first, whereby a series of cuts are made radially outward from a fixed point exterior to and at the rear of the dredge-boat.

My invention also comprises a means for advancing the fixed center and bringing it up to the rear of the dredge-boat after a complete cut has been made, so as to place the apparatus in position for another forward cut.

It also comprises a novel arrangement of cutters operating in the line of movement of the dredge-boat and a suction-pipe and sections having horizontally-elongated mouths transverse to the line of movement and extending behind the series of excavators.

My invention also comprises details of construction which will be more fully explained by reference to the accompanying drawings, 40 in which—

Figure 1 is a longitudinal elevation of my dredger. Fig. 2 is a plan of the same. Fig. 3 is a plan of the forward part of the ladder. Fig. 4 is an end view of the rotary cutters. Fig. 5 is a plan of the same.

In the art of dredging with apparatus in which the dredged material is disposed of by means of suction-pumps and conveying-pipes it has been customary to swing the dredge-boats about a pivot located within the boat

and to employ rotary excavators turning in planes transverse to the boat, said excavators being projected to the point of operation and supported by "ladders," so called, and these ladders have been moved by anchors and tackle, so that a dredge-boat is swung from one side to the other while the cutters are operating.

In my invention the excavating is done while the dredge moves forward, and no excavating is done while swinging the dredge-boat from one side to another.

The cutters of my invention are designed to cut in the direct line of forward movement of the dredge-boat, and the conveying-pipes are telescoped and slidable, so as to allow of such movement while the excavating is taking place and to allow the pipes to be again shortened while the boat is withdrawn and placed over another cut.

In the present case I have shown a boat or scow A, which is termed a "dredge-boat," upon which is mounted the engine or motor and necessary machinery connecting with a ladder 2, which is hinged to one end of this boat and is capable of swinging up and down about its horizontal hinges, but without any independent side motion with relation to the boat.

A suitably braced and supported mast 3 is fixed upon the boat, with hoisting-tackle of any usual or well-known description connecting with the ladder, whereby the latter may be raised during the progress of the cut or allowed to descend to the bottom.

Upon the inner or hinged end of the ladder is mounted a motor 4 of any suitable character, and through the necessary train of gearing power is communicated to drive a shaft 5, which is journaled and extends centrally along the ladder to the front end, where it carries a bevel-pinion 6, and this engages with a corresponding beveled gear 7, mounted upon the shaft 8. This shaft carries a series of cutters 9, of which there may be as many as required to make a cut of the desired width.

The shaft 8 is journaled in boxes carried by the front timbers of the ladder 2, which timbers extend transversely, as shown.

The cutters 9 are of such form and character that being pushed against the bank of earth to be excavated they will continually loosen and break it down, and the material 5 thus loosened is drawn into the suction-pipe 10 by means of the suction-pump 11, carried upon the dredge-boat and driven by suitable motor and intermediate connecting mechanism.

10 By means of a flexible joint at 12, having the same axis of movement as the head of the ladder, the pipe is allowed to follow the movements of the ladder without impeding the passage of the material. Any suitable 15 joint, such as the well-known ball-joint, may be employed at this point.

The main suction-pipe 10 is here shown as dividing into two branches 13, which diverge from the main pipe, and these branches are 20 flattened and diverge at the mouth, so as to form wide rectangular openings 14, the combined length of which is equal to the transverse distance occupied by the cutters, and these mouths open just behind the cutters, 25 so that material loosened thereby will be drawn into these mouths and thence conducted to the main suction-pipe 10 and delivered through the pump 11, passing through the discharge-pipe section 15, which is mounted upon the boat A.

30 In the rear of this boat is a second boat 16, and this boat has guides 17, through which vertical "spuds," so called, are driven to anchor and hold this second boat firmly in position. Upon the front of this second boat and behind the boat A is a horizontally-operating device 18, the lower part of which is fixed to the boat and the upper part is turnable with relation thereto. Through the upper portion of this device passes a strong 35 horizontally-disposed timber or arm 19, the front end of which is fixed upon the dredge-boat A, the rear end being slideable, as before described, through the turnable member of the device 18. This timber or arm serves to 40 move the dredge-boat forward with relation to the anchored boat 16, and this is effected by means of chains or cables 20, passing around blocks 22, by which any desired multiplication of power may be effected, and 45 finally upon a winding-drum, as at 23, by which the chain or cable can be wound up, and through the power thus developed the timber 19 is forced forward with relation to the fixed boat 16, and the boat A is thus 50 moved directly in line therewith, so that the excavators will continually dig and break down a section of material in the line of forward movement of the boat A to a distance 55 equal to the forward movement effected by 60 the mechanism herein described.

It will be manifest that some means must be employed for lengthening the discharge-pipe 15 in unison with the forward movements of the boat A, and this is effected by a 65 telescopic joint composed of an outer straight section of tube 24, within which the section 25 is slideable through a suitable stuffing-box,

the length of this telescopic section being sufficient for the required advance of the boat A.

When a cut has been completed to as great a distance as desired, the boat A is drawn back to the boat 16 by means of a rope or chain 26, passing through blocks 27, by which power is multiplied to any desired extent, thence around guide-pulleys 28, and thence 75 to the winding-drum 23, so that by winding in this rope or cable and correspondingly letting out the cable 20 the boat A may be drawn back to the boat 16, the timber 19 sliding through its guide as it is retracted. It will be manifest 80 that by reason of the turnable nature of this guide about its vertical axis the boat A may be turned to a very considerable angle with the anchor-boat 16. Thus the length from the guide 18 to the excavators at the front of 85 the ladder will form the radius of the arc through which the boat and excavators may be made to swing during the work of excavation; but it is to be understood that no side or swinging movement takes place while the 90 excavation is going on. The boat or scow A, carrying the excavator, is forced forward by the power brought to bear upon the beam 19 through the cables and is thus forced forward to continually keep the excavator up to 95 its work.

After the excavation has been completed to the full length of its cut the boat and excavator are withdrawn in the same line and are afterward placed in the line of a new cut 100 parallel with the first made, and thus each cut is made in the line of the boat until the whole width of the cut has been made from extreme side to side. It is then necessary to advance the apparatus in readiness for a new 105 series of cuts. This is effected by temporarily fixing the boat A by means of a spud which is sunk into the bottom while the boat is drawn away to its greatest distance from the anchored boat 16. The spuds or anchors 110 of the boat 16 are then withdrawn by suitable tackle, and this boat is moved forward until it is brought close to the boat A, the telescope-joint at 24 25 sliding and closing up until the boats are close together. The material which passes through the discharge-pipe 115 15 and through this telescopic joint passes also through a discharge-pipe 30, which is supported upon the boat 16.

31 is a ball-joint, the axis of which is in vertical line with the axis of the guide 18, so that in turning the boat A about the boat 16 when the latter is anchored this joint moves in unison with the guide and maintains communication between the pipes 15 and 30.

In order to allow the boat 16 to advance, as previously described, it is also necessary to provide for an extension of the pipe 30. This is effected by sliding one section into another and forming a telescopic joint upon the rear 130 part of the boat 16, as shown at 32, the outer tube of this joint being connected with the extension of the discharge-pipe, which is carried rearwardly from the boat 16 to any re-

quired point of discharge, while the inner 5
slidable section of the joint is connected with
the part 30 and advanced with it when the
boat 16 is advanced up to the boat A. When

10 this advance of the boat 16 is completed, the
spuds or anchors are again fixed to render the
boat 16 immovable, and the spud or anchor
temporarily used to hold the boat A is re-
moved, so that the latter is in condition to
15 again be advanced. These movements hav-
ing been completed, the apparatus is then
ready for a new cut, the telescope-joint 24 25
being closed, and the excavators can then be
moved forward to commence a new cut. This

20 construction enables me to first make a cut
of the desired width by successive forward
movements of the excavator, making inde-
pendent cuts side by side and radially in line
25 from the turnable guide on the fixed float and
20 after such a cut is made to advance the whole
apparatus into position to make a second cut
without stopping to insert new lengths of con-
ducting-pipe or otherwise providing for such
advance.

25 Having thus described my invention, what
I claim as new, and desire to secure by Letters
Patent, is—

1. In a dredger, a means for making a suc-
cession of forward cuts centering from a fixed
30 point at the rear of said dredge.

2. In a dredger, an excavator, suction and
conducting pipes and a supporting-float,
a fixed point behind the float around which
35 the dredger swings, slideable joints in the con-
ducting-pipes, and means for advancing the
excavator and float in any direction with re-
lation to said point while cutting.

3. In a dredger, an excavator, suction and
conducting pipes and a support therefor, a
40 fixed point in rear of said support around
which the dredger swings, a slideably-extensi-
ble joint in the conductor, means by which
the excavator and its support may be ad-
vanced to cut in different radial lines out-
45 wardly from the fixed point, and means for
retracting these parts after each cut.

4. In a dredger, an excavator, a float and
a ladder projecting forward of the float and
upon which the excavator is carried, a suc-
50 tion-pipe having its mouth opening contigu-
ous to the excavator, a discharge-pipe con-
necting therewith and leading rearwardly to-
ward a fixed point, a fixed structure at the
rear of the float, a turnable guide mounted
55 thereon, and means for moving the float and
the excavator in a forward direction away
from and in line with the said fixed point
during the cutting operation.

5. In a dredger and excavator, a float, a lad-
60 der hinged to the front thereof upon which the
excavator is adjustably carried, a suction-
pipe carried upon the ladder having its mouth
contiguous to the excavator, a discharge-pipe
leading rearwardly across the float having a
65 telescopic slideable section thereon, a turnable
guide mounted upon a fixed support axially
in rear of the float, a ball-and-socket joint in

the discharge-pipe having its axis coincident
with that of the guide, and a means for ad-
vancing the float and excavator in radial lines
70 from the guide and coincidently extending
the discharge-pipe.

6. In a dredger, an excavator, a float hav-
ing a ladder hinged to the front upon which
said excavator is carried, a second float fixed
75 at the rear of the first-named float having a
turnable guide mounted thereon, a slideable
beam fixed to the front float and movable
through the turnable guides and means
whereby said beam and the front float and
80 excavator are advanced with relation to the
guide.

7. In a dredger, a float having a ladder
hinged to the front, an excavator carried upon
the front of the ladder, and means for remov-
85 ing the excavated material, a second float fixed
in line at the rear of the first float, and hav-
ing a turnable guide mounted thereon, a beam
slideable through said guide having its front
end fixed to the forward float, a cable or the
90 like connecting with the rear end of said beam
and a winding-drum upon one of the floats to
coil said cable, whereby said beam and the
forward float are advanced with relation to
the fixed float and the guide. 95

8. In a dredger, a float having a ladder
hinged to the front, an excavator carried upon
the front of the ladder, and means for remov-
ing the excavated material, a second float fixed
100 in line at the rear of the first float and having
a turnable guide mounted thereon, a beam
slideable through said guide having its front
end fixed to the forward float, a winding-drum
and cables connected with the beam whereby
105 the ladder, and the forward float may be ad-
vanced and retracted with relation to the fixed
float.

9. In a dredger, a float having a ladder
hinged to the front, an excavator carried upon
the front of said ladder, suction and discharge
110 pipes by which the excavated material is
transferred rearwardly from the excavator
and float, a second float fixed at the rear of
the first-named float having a turnable guide
115 mounted thereon, a ball-and-socket joint in
the discharge-pipe axially in line with said
guide, and a beam or the like slideable through
said guide having its forward end fixed to the
excavator-float, cables and winding-drums
120 whereby the beam and excavator-float are
moved forward and back with relation to the
guide, a slideable telescopic joint in the dis-
charge-pipe anterior to the telescopic joint,
whereby said pipe is lengthened in unison
125 with the forward movements of the excavator.

10. In a dredger, a float having a ladder
hinged to the front, an excavator carried there-
on, suction and discharge pipes by which the
excavated material is conveyed rearwardly
130 from the float, a second float having a turn-
able guide mounted thereon, a ball-and-socket
joint in the discharge-pipe axially in line with
the guide, a telescopic section in the dis-
charge-pipe anterior to said joint, cables and

winding-drums whereby the excavator and its float are advanced or retracted with relation to the guide-carrying float, spuds or anchors by which said float is fixed during the advance or retraction of the excavator, spuds or anchors by which the excavator-float may be anchored while the guide-float is released and moved up to the rear of the excavator-float after a cut has been completed, and a guided telescopic section of the discharge-pipe carried upon the rear float, whereby the advance of said float is permitted without breaking the continuity of the pipe.

11. In a dredger, a float having a ladder hinged to the front, one or more excavators mounted upon a shaft journaled transversely across the front of the ladder, means for moving the float and the excavator in a forward direction away from and in line with a fixed point during the cutting operation, and toward said point after the completion of each cut, and a suction-pipe carried upon the ladder and having a mouth made divergent hori-

zontally and coincident with and contiguous to the excavators.

12. In a dredger, a float having a ladder hinged to the front, one or more excavators mounted upon a shaft journaled transversely across the front of the ladder, mechanism by which power is transmitted to rotate said shaft and excavators, and means for advancing the float and excavators in the longitudinal line of the dredge so as to make a direct forward cut at each advance, a suction-pipe carried upon the ladder having divergent branches at the lower end, said branches having mouths in the form of flattened cones or hoppers divergent from the branches toward the front and contiguous to the excavator.

In witness whereof I have hereunto set my hand.

RAYMOND A. PERRY.
